UNITED STATES PATENT OFFICE.

JAMES D. MURRAY, OF CANANDAIGUA, ASSIGNOR OF ONE-HALF TO RUFUS E. BOSHERT, OF SYRACUSE, NEW YORK.

VINEGAR-GENERATOR.

SPECIFICATION forming part of Letters Patent No. 338,183, dated March 16, 1886.

Application filed December 5, 1885. Serial No. 184,765. (No model.)

To all whom it may concern:

Be it known that I, JAMES D. MURRAY, of Canandaigua, in the county of Ontario, in the State of New York, have invented new and 5 useful Improvements in Vinegar-Generators, of which the following, taken in connection with the accompanying drawings, is a full, clear, and exact description.

The object of this invention is to provide a 10 vinegar - generating apparatus which shall with superior capacity occupy minimum space, and shall also be convenient and efficient in its operation; and to that end my invention consists, essentially, of a chamber 15 provided with air-inlets and air-outlets, a tank for containing the liquor to be acetified, occupying the lower part of the said chamber, and a crate or perforated holder for acetifying material, arranged movable from the interior of 20 the tank to the upper part of the chamber, all as hereinafter more fully described, and set forth in the claim.

In the annexed drawings, Figure I is a side elevation of my invention, a portion of the 25 side of the chamber being broken away to show the internal arrangement thereof. Fig. II is an end elevation of the same. Fig. III is a vertical transverse section on line $x x$, Fig. IV; and Fig. IV is a vertical longitudinal section of the lower portion of the apparatus on line $y y$, Fig. III.

Similar letters of reference indicate corresponding parts.

A represents the chamber in which the 35 vinegar is generated. Said chamber is stationary, and in order to economize in space and permit of arranging a number of said chambers within a limited area I make said chamber either square or rectangular or other 40 suitable prismatic shape.

Though I do not limit my invention to any particular shape, inasmuch as the economy in space may be of minor importance in some cases, the most essential feature is the stationary arrangement of the chamber A.

B denotes a tank for containing the liquor to be acetified, which tank occupies the lower part of the chamber A, and at or near the top of said tank the chamber A is provided with 45 perforations $a a$, for the inlet of atmospheric air, which is caused to permeate through the chamber and escape through apertures $b b$ in

the top of the chamber, as indicated by arrows in Fig. I of the drawings.

C represents a perforated holder for the shavings required in the process of generating vinegar. Said holder may be of the form of a crate, or preferably a series of crates mounted 55 removably one upon another, thereby obviating the danger of the shavings becoming 60 packed and incapable of quickly absorbing the liquor when immersed therein. Said holder is of proper shape and dimensions to allow it to enter into the tank B.

To the ends of the bottom crate are attached 65 upright standards, $c c$, which are provided with racks $r r$.

At the top of the chamber A, and lengthwise thereof, is arranged a shaft, d , journaled in suitable bearings on the ends of the chamber, and 70 provided with pinions $e e$, which mesh in the racks $r r$ aforesaid. To the extremity of the said shaft is attached a gear-wheel, f , and in this meshes a pinion, g , mounted loosely on a gudgeon secured to the top of the chamber A, 75 and to said pinion is attached a crank, h , by which to rotate it.

i denotes the thermometer applied to the 80 chamber for indicating the temperature of the interior of said chamber.

l designates the inlet for the liquor to the tank B.

m is the faucet through which to discharge 85 the vinegar from the tank, and n represents a gage for determining the height of the liquor or vinegar in the tank.

The operation of my invention is as follows: The cider or other liquor to be fermented or acetified is introduced into the tank B through the inlet l . The crate or crates C having previously been raised to the upper part of the chamber and the top of the chamber opened to obtain access to the crates, the latter are filled with beech-wood shavings or other analogous acetifying material; then the top or cover of the chamber is replaced and the crates are lowered into the tank B by turning the crank h . The shavings in the crates thus become submerged in the liquor contained in the tank. So soon as the shavings become saturated the crank h is turned in the opposite direction to raise the crates and their contents out of the tank and to the upper part of the chamber, as represented in Fig. I of the draw- 90 95 100

ings, in which position the crate or crates are retained until the liquor adhering to the acetifying material therein becomes acetified by the action of atmospheric air passing up 5 through the acetifying material, as represented by arrows in Fig. I of the drawings. After the liquor adhering to the acetifying material becomes acetified, which is accomplished in about three hours, the crate or crates are again 10 lowered into the tank containing the liquor to be acetified, as shown in Figs. 3 and 4 of the drawings, and then raised in the manner before described, and this is continued until the acetification of the liquor in the tank is com- 15 plete.

Having described my invention, what I claim is—

The combination of the tank, the chamber above the tank, and the holder for acetifying material, arranged movable from the tank to 20 the upper part of the chamber and back to the tank, substantially as set forth and shown.

In testimony whereof I have hereunto signed my name and affixed my seal, in the presence of two attesting witnesses, at Canandaigua, in 25 the county of Ontario, in the State of New York, this 9th day of November, 1885.

JAMES D. MURRAY. [L. S.]
